(57) **CLAIM**

The ornamental design for a concealer pen, as shown and described.

DESCRIPTION

FIG. 1 is a perspective view of a concealer pen showing the new design;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof; and,

FIG. 8 is an exploded view of the concealer pen shown in an open configuration.

The features shown in broken lines are included for the purpose of illustrating portions of the concealer pen that form no part of the claimed design.

1 Claim, 7 Drawing Sheets
